UNITED STATES PATENT OFFICE.

FLORYAN GROCHAL, OF EASTHAMPTON, AND JOHN OTREBA, OF AMHERST, MASSACHUSETTS.

REPAIR OUTFIT FOR SHOEMAKERS.

1,417,900.

Specification of Letters Patent. Patented May 30, 1922.

Application filed April 11, 1921. Serial No. 460,265.

To all whom it may concern:

Be it known that we, FLORYAN GROCHAL, a citizen of the United States, residing at Easthampton, in the county of Hampshire, in the State of Massachusetts, and JOHN OTREBA, a citizen of Poland, residing at Amherst, in the county of Hampshire and State of Massachusetts, have invented certain new and useful Improvements in Repair Outfits for Shoemakers, of which the following is a specification.

The main purpose of this invention is to provide a repair outfit for shoe makers and cobblers by which shoe heels may be held in connection with the shoe in a firm and secure manner.

Another object is to provide a metal last used in connection with the device, the last being so designed as to extend the full length to the front of the shoe.

These and other objects which will become more fully apparent as the description progresses are attained by the novel construction, combination and arrangement of parts hereinafter described and shown in the accompanying drawings forming a material part of this disclosure and in which:

Figure 1 is a side elevational view showing the apparatus and indicating its principal use.

Figure 2 is a perspective view of the base together with the fixed elements carried thereby.

Figure 3 is a perspective view of the last in detail.

Figure 4 is a front elevational view of the heel holder.

Figure 5 is a top plan view of the same.

Figure 6 is an enlarged transverse sectional view taken on line 6—6 of Figure 4.

Figure 7 is a longitudinal sectional view taken through the center of the assembled apparatus.

Figure 8 is a top plan view of the base.

Figure 9 is a transverse sectional view taken on line 9—9 of Figure 7.

Figure 10 is a similar transverse sectional view taken on line 10—10 of Figure 7.

Stated in general terms the invention comprises a base shaped to be placed upon the knees of the user upon which it may be comfortably operated. Formed on the top is an abutment suited to receive the sole of a shoe and another abutment carrying a screw used

to impel a clamp toward the first abutment 55 and hold therebetween the shoe heel to be secured.

Openings through the base are provided for receiving the lower end of a metal last, provision being made for clamping the same 60 firmly in position for use.

Referring more particularly to the drawings in detail, the numeral 15 indicates the central portion of an elongated rectangular metal plate, its ends 16 being slightly arcuately curved so that the structure may be held upon the knees of an operator in a comfortable manner and with desirable security.

Integrally formed near the center of the base element is a raised abutment 17 having 70 a projecting element 18 at the front and provided with lateral lugs 19 adapted to make contact with the sides of the shoe, this abutment being rigidly engaged to the base by a brace 20, opposite the extension 18.

A similar but narrower abutment 21 is provided near the right hand end of the base, the same being drilled and screw threaded as at 22 for the reception of a threaded rod 23 having an operating head 80 or handle element 24 at its outer end, its opposite inner end having fixedly engaged upon it a disc 25.

Immediately to the left of the abutment 21 is a T-shaped slotted opening, its longitudinal portion 26 opening into a transverse portion 27 adjacent the abutment 21, the opening 27 being receptive of a tenon element 28 connected by a stem 29 with a curved clamp member 30, the inner arcuate portion of which is shaped in conformity with the exterior of the heel A which it is intended to apply to the shoe B.

It will be understood that the element 28 extends completely through the slot 27 so 95 that as the clamp is moved toward the abutment 17, the stem 29 will travel in the slot 26, thus permitting free longitudinal movement of the clamp element.

At the rear of the clamp element is a vertical recess 32 open at its lower end immediately rearward of the stem 29, this recess being receptive of the ring 25.

In order to press the heel upward into close engagement with the sole of the shoe, 105 a screw threaded opening 33 is provided in the base 15 midway between the abutment 17 and adjacent end of the slot 26. This

opening being receptive of a screw 34 having a flattened point and provided with an operating head 35.

From the foregoing it will be seen that an effective device has been disclosed for rigidly clamping a heel so that it can be secured to the shoe by nails passed downwardly through the same into the material of the heel, the elements 17, 30 and 34 acting as supports for that purpose, the shoe being positioned as indicated best in Figures 1 and 7.

In addition to the foregoing, in order to make the apparatus fully complete, a metal last having an upper anvil surface 35' from which extends a shank 36, is provided with a T shaped member at its bottom, the transverse element 37 being entrable in the slot 27 and the forwardly extending tenon element 38 being fitted to the slot 26 down to the base of the stem, is rigidly held in position by and clamped down by the screw impelled ring 25 rigidly to the base.

The application and operation of the implement is believed to be obvious from the foregoing disclosure, therefore having thus described the invention and set forth the manner of its construction and use, what we claim as new and desire to secure by Letters Patent, is:—

30 1. In a shoe repairing device for cobblers,

the combination with a saddle plate having curved end portions engageable upon the knees of the operator, of a fixed abutment on the saddle plate suited to support the shank and sides of a shoe, an interchangeable clamp 35 slidably engaged with said saddle shaped to engage the heel of a shoe, manually operated means for impelling the clamp and shoe toward the fixed abutment, and means for adjustably supporting the heel of the shoe 40 independently of said clamp.

2. In a shoe repairing device for cobblers, the combination with an elongated saddle plate, of fixed abutments thereon, one of said abutments being suited to support the shank 45 and sides of a shoe, the other abutment engaging a clamp screw, said saddle having a T shaped opening between said abutments, an interchangeable clamp operable in the opening engaging the heel of a shoe between 50 said clamp and the first described abutment, said clamp being operatively engaged by the mentioned screw, a support for the heel of the shoe, said support being adjustable in said saddle, and means on said clamp preventing vertical displacement when engaged in the T shaped opening.

In witness whereof we affix our signatures.

FLORYAN GROCHAL.

JOHN OTREBA.
